US0D1112467S

(12) **United States Design Patent** (10) Patent No.: **US D1,112,467 S**
 Connor et al. (45) Date of Patent: ** Feb. 10, 2026

(54) **TYPE FONT**

- (71) Applicant: **Apple Inc.**, Cupertino, CA (US)
- (72) Inventors: **Teofila Connor**, San Francisco, CA (US); **Thalia Jimena Echevarria Fiol**, Cupertino, CA (US); **Vincenzo Vuono**, Sunnyvale, CA (US)
- (73) Assignee: **Apple Inc.**, Cupertino, CA (US)
- (**) Term: **15 Years**
- (21) Appl. No.: **29/935,314**
- (22) Filed: **Apr. 1, 2024**

D127,516 S 5/1941 Chernow

(57) **CLAIM**

The ornamental design for a type font as shown and described.

DESCRIPTION

The FIGURE is a front view of a type font showing the claimed design.

1 Claim, 1 Drawing Sheet
